Inventor:

John Ross

by Byrnes, Townsend & Bickenstein

Attorneys.

UNITED STATES PATENT OFFICE.

JOHN ROSS, OF RICHMOND HILL, NEW YORK.

PADDING FOR USE IN PRESSING OPERATIONS AND THE LIKE.

Application filed July 12, 1921. Serial No. 484,253.

To all whom it may concern:

Be it known that I, JOHN Ross, a citizen of the United States, residing at Richmond Hill, Long Island, in the county of Queens and State of New York, have invented certain new and useful Improvements in Padding for Use in Pressing Operations and the like, of which the following is a specification.

My invention relates to padding for use in pressing operations or the like and particularly to padding for use in the dry cleaning, steaming and pressing woolen and cotton cloth or clothing.

An object of my invention is to provide a yielding padding through which steam or vapor may pass freely. A further object of my invention is to form a padding of the type described from a yielding material which offers substantial resistance to the passage of steam and vapor by providing such material with perforations through which the steam and vapor may pass. More specifically an object of my invention is to provide a yielding padding consisting of a layer of perforated wadding between two layers of open-work fabric.

An embodiment of my invention is illustrated in the accompanying drawings, in which—

Fig. 1 is a plan view, partly in section, of the buck of a pressing machine to which my improved form of padding has been applied.

Fig. 2 is a vertical section through the buck and applied padding, and

Fig. 3 is an enlarged vertical section through a portion of the padding.

In the drawings the buck is indicated by the numeral 1, and as here shown comprises a heating chamber 2 and a moistening chamber 3. The heating chamber is provided with a pipe 4 for the introduction of steam and a pipe 5 for the removal of water of condensation. The upper face of the moistening chamber 3 is formed by the perforated pressing plate 6, and steam is supplied to the chamber through inlet pipe 7. To secure an even distribution of steam throughout the chamber a baffle plate 8 is located over the outlet of pipe 7. The steam which is used for moistening the garment or cloth is exhausted from the chamber 3 through pipes 9 which lead to a suction de-

vice, not shown. The padding 10 to which this invention relates is held in position on the pressing plate 6 by means of the cover 55 cloth 11, which may be of ticking or other suitable material.

The padding 10 consists of an intermediate layer of wadding 12 provided with perforations 13, and quilted between two layers 60 of unperforated cheesecloth or other open work fabric 14, 14 by rows of stitching 15. The wadding 12 provides a yielding or cushioning body and the fabric 14, 14, serves as a reinforcement for enabling the 65 layer of wadding to maintain its shape while being applied to a pressing or other machine and during use in pressing operations. The padding may be formed by running wadding through a puncturing machine and then placing the perforated wadding in a quilting machine with sheeting of cheesecloth or the like on both sides, and then quilting in the usual manner. Good results are secured when the perforations 70 are about one quarter inch in diameter and are spaced from an inch to an inch and a quarter between centers, but the size and relative spacing of the perforations may be varied to suit different conditions. 75

It is to be understood that the invention is not limited in its application to machines of the type here shown but may be used with other machines and in other steaming, cleaning and pressing operations. 80

I claim:

1. A padding for use in pressing operations and the like comprising unwoven yielding nonmetallic wadding provided with perforations for the passage of steam, and 90 open-work fabric on both sides of said wadding.

2. A padding for use in pressing operations and the like comprising a layer of unwoven yielding nonmetallic wadding provided with perforations for the passage of steam, a layer of open-work textile fabric arranged at each side of said layer of wadding, and rows of stitching for holding said layers in assembled relation. 95

In testimony whereof, I affix my signature.

JOHN ROSS.
